DESIGN FOR A RACK AND PINION ASSEMBLY

**Theron G. Gerow, Chicago, Ill., assignor to
Kensington Steel Company, Chicago, Ill., a cor-
poration of Illinois**

Application March 29, 1943, Serial No. 109,854

Term of patent 14 years

To all whom it may concern:

Be it known that I, Theron G. Gerow, a citizen of the United States of America, residing at 8 South Michigan Avenue, Chicago, Illinois, have invented a new, original, and ornamental Design for a Rack and Pinion Assembly, of which the following is a specification, reference being had to the accompanying drawing forming a part thereof.

Fig. 1 is a side elevational view of a rack and pinion assembly showing my new design and Fig. 2 is a top plan view of the same.

I claim:

The ornamental design for a rack and pinion assembly, substantially as shown.

THERON G. GEROW.
